UNITED STATES PATENT OFFICE

96,573

DESIGN FOR A JAR FOR A COFFEE INFUSION URN

Michael Felix, Flushing, N. Y.

Application October 22, 1934, Serial No. 53,718

Term of patent 14 years

To all whom it may concern:

Be it known that I, Michael Felix, a citizen of Greece, having filed first citizenship papers in the United States, residing at Flushing, Long Island, in the county of Queens and State of New York, have invented a new, original, and ornamental Design for a Jar for a Coffee Infusion Urn, of which the following is a specification, reference being had to the accompanying drawing, forming part thereof, wherein:

Fig. 1 is a side elevational view of the jar showing my design, and

Fig. 2 is a top plan view of the jar shown in Fig. 1.

I claim:

The ornamental design for a jar for a coffee infusion urn, as shown.

MICHAEL FELIX.
